COMBINATION MATCHBOOK AND
TOOTHPICK HOLDERNicholas C. Mitchell, International Hotel, 1173 Island
Ave., McKees Rocks, Pa.
Filed Oct. 7, 1960, Ser. No. 61,262

2 Claims. (Cl. 206—29)

This invention relates to a combination matchbook and toothpick holder and more particularly to a folding paper or cardboard matchbook which has a receptacle for carrying at least one toothpick.

Heretofore, there have been matchbooks which have had provision for carrying or housing one or more toothpicks, but the toothpicks were so located therein that they easily became contaminated with some of the substances comprising the heads of the matches. Thus, the toothpicks were rendered unusable. Other of these matchbooks, while adequately protecting the toothpicks from contamination by enclosing them in envelopes, so position the envelopes adjacent the matches that a number of the envelopes were punctured or broken when a match was removed from the match cover, thereby subjecting the toothpicks in the envelopes to the contamination.

I have invented a combination matchbook and toothpick holder which provides a receptacle spaced apart from the matches and so located that contamination with the substances comprising the heads of the matches is reduced to a minimum. Specifically, my combination comprises a cover made from a flexible material and folded over transversely thereof to form a front and a back which normally houses a plurality of matches. The cover includes a base formed by an extension of the back which is folded transversely back upon itself and forwardly. The lower ends of the matches are joined to the base and the matches project upwardly therefrom.

The base includes a receptacle extending widthwise of the cover and disposed below the joining of the matches thereto. The extension of the back of the cover forms the bottom and the front and rear sides of the receptacle which has at least one of its ends open for insertion into, and withdrawal from, at least one toothpick.

At least one of the front and rear sides of the receptacle has at least one end tab integral therewith and separated therefrom by a fold crease. The end tab extends from the end of the side inwardly towards its center part and is foldable backwardly upon the fold crease to provide easy access to a toothpick disposed in the receptacle.

The receptacle is of such width and depth that its sides frictionally engage the toothpick disposed therein and thereby assists in maintaining it in the receptacle.

In the accompanying drawings, I have shown two preferred embodiments of my invention in which:

FIGURE 1 is a side elevation view of one embodiment of my combination matchbook and toothpick holder;

FIGURE 2 is a view along the line II—II of FIGURE 1;

FIGURE 3 is a view along the line III—III of FIGURE 1; and

FIGURE 4 is a side elevation view of a second embodiment of my combination.

Referring to FIGURES 1—3, my combination comprises a matchbook cover 1 made from a flexible material such as cardboard, heavy paper, etc. which is folded over transversely of itself to form a front 2 and a back 3 wherein a plurality of tear-away matches 4 are housed. The cover 1 includes a base 5 which is formed by an extension 6 of the back 3 folded transversely back upon itself and forwardly to terminate in a closure flap 7. The lower ends 8 of the matches are secured to the base by conventional staples 9 with the matches extending up-

2

wardly from their connection to the base. The staples are spaced apart from the outer end 10 of the closure flap whereby the lower end 11 of the front 2 may fit inside and into engagement with the closure flap to effect a shutting of the cover.

The extension 6 of the back 3 defines below the staples 9 a receptacle 12 running widthwise of the cover with the extension forming the bottom 13, front side 14 and rear side 15 of the receptacle. As shown in FIGURES 10 1—3, both ends 16 and 17 of the receptacle are open but one may be closed.

Disposed within the receptacle 12 are two toothpicks 18 and 19 located side by side and extending substantially the length of the receptacle with their ends inside the ends 15 16 and 17 of the receptacle. Preferably, the toothpicks are of such length that once inserted into the receptacle, their ends do not project beyond the sides of the cover 1. To provide sanitation, the two toothpicks are placed in a sanitary paper envelope 20 which completely encompasses them; however, use of the envelope is not essential. The receptacle is of such width and depth that its sides frictionally engage the envelope and thereby assist in maintaining it within the confines of the receptacle. Except for frictional engagement of the sides 25 of the receptacle with the envelope, it is otherwise separate and independent of the combination and undetached therefrom. Where the envelope is not used, the sides of the receptacle frictionally engage the toothpicks and maintain them within the receptacle.

30 To insert a toothpick into or withdraw it from the receptacle, one end is placed in the open end of the receptacle and then it is moved transversely of the cover until the other end is wholly within the receptacle.

To provide easy removal of a toothpick from the receptacle, there is an end tab 21 integral with each end of the front and back sides of the receptacle. The sides of the end tab are severed from the front and sides of the receptacle and a fold crease 22 separates the end tab from these sides. Accordingly, the tab may be bent or folded backwardly upon its fold crease as shown in FIGURES 1 and 2 regarding tabs 21a and 21b and thereby afford easy access to one end of a toothpick in the receptacle.

45 FIGURE 4 shows a second embodiment of my combination which is substantially the same as the embodiment of FIGURES 1—3 except that instead of the end tabs, at least one end 16 of either the front side 14 or back side 15 of the receptacle has a notch 23 cut out therefrom. This notch extends from the end of the front or back sides inwardly towards the center part thereof and like the end tabs, provides easy access to an end of a toothpick disposed in the receptacle.

50 My combination has important advantages in that after the toothpicks in the receptacle have been used, replacements can then be inserted into the receptacle, thereby assuring a supply of toothpicks for the life of the matchbook. In addition, the receptacle houses the toothpicks remote from the matches and thereby avoids contamination thereof with the chemicals comprising the match heads. Also, the receptacle completely contains the toothpicks and thus avoids breakage of their ends and protection of the ends from contamination with foreign objects or articles which may render them unsanitary.

60 65 The combination is simple and easy to manufacture and does not require substantial alterations to conventional matchbook covers.

70 While I have shown and described preferred embodiments of my invention, it will be understood that it may be otherwise embodied within the scope of the appended claims.

I claim:

1. A combination matchbook and toothpick holder comprising a cover made from a flexible material and folded over transversely thereof to form a front and back normally housing a plurality of matches, said cover including a base formed by an extension of said back which is folded transversely back upon itself and forwardly with a lower end portion of said matches being joined to said base and with the matches projecting upwardly therefrom, said base further including a receptacle in the fold thereof extending widthwise of said cover and disposed below the lower ends of the matches, said extension of said back forming the bottom, front and rear sides of said receptacle which has at least one of its ends open, the front and rear sides being planar and substantially parallel, one end of said front and rear sides having an end tab integral therewith and separated therefrom by a fold crease, said end tab extending from the end of each front and rear side inwardly towards the center part thereof and being foldable backwardly upon said fold crease to provide an access opening to a toothpick disposed longitudinally in said receptacle, the tabs on the front and rear sides being in alignment transversely of the toothpick to permit the user to readily grasp the end of the toothpick between opposed fingers

when the tabs are folded backwardly, at least one toothpick positioned in said receptacle and being of such length that when disposed therein, its ends do not project beyond the ends of said cover, but do project into said access opening, said toothpick being inserted into and withdrawn from said receptacle by moving it transversely of said cover, said receptacle being of such width and depth that its sides frictionally engage said toothpick and assist in maintaining it in said receptacle.

10 2. The holder of claim 1 characterized by at least one of said toothpicks being in a sanitary envelope which is separate and independent of said combination and which is undetached from said combination except for frictional engagement with the sides of said receptacle.
